AUTOMOBILE ANTENNA IDENTIFICATION DEVICE

Thaddeus A. Sikorski and Helen K. Sikorski, both of 208
Haddon Ave., Collingswood, N.J. 08108

Filed May 28, 1971, Ser. No. 148,295

Term of patent 7 years

Int. Cl. D12—16

U.S. Cl. D14—6

FIG. 1

FIG. 2

FIG. 3

FIG. 4

FIG. 1 is a side elevation of an automobile antenna identification device showing our new design;

FIG. 2 is a top plan view thereof;

FIG. 3 is a bottom plan view thereof; and

FIG. 4 is a section taken on line 4—4 of FIG. 3.

We claim:

The ornamental design for the automobile antenna identification device, as shown and described.
